(57) **CLAIM**

The ornamental design for a slicer, as shown and described.

DESCRIPTION

FIG. 1 is a front perspective view of a slicer showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a reference view thereof showing a state in use;

FIG. 10 is another reference view thereof showing a state in use;

FIG. 11 is an enlarged view of portion 11 of FIG. 10; and,

FIG. 12 is an enlarged view of portion 12 of FIG. 10.

The broken lines in the drawings are included for the purpose of illustrating the partial enlarged views.
